Primary Examiner — Marianne Pandozzi*(74) Attorney, Agent, or Firm* — Joseph G. Swan, P.C.(57) **CLAIM**

The ornamental design for a wine aerator, as shown and described.

DESCRIPTION

FIG. 1 is a perspective view of a wine aerator according to the present invention.

FIG. 2 is a right side elevational view of the wine aerator.

FIG. 3 is a front elevational view of the wine aerator.

FIG. 4 is a left side elevational view of the wine aerator.

FIG. 5 is a rear elevational view of the wine aerator.

FIG. 6 is a top plan view of the wine aerator; and,

FIG. 7 is a bottom plan view of the wine aerator.

The portions shown in broken lines are solely for the purpose of illustrating context and form no part of the claimed design.
